CLAIM

The ornamental design for a trampoline frame, as shown and described.

DESCRIPTION

FIG. 1 is a perspective view of a first embodiment of a "trampoline frame", showing our new design;

FIG. 2 is a front elevational view of FIG. 1;

FIG. 3 is a side elevational view of FIG. 1;

FIG. 4 is a top plan view of FIG. 1;

FIG. 5 is a bottom plan view of FIG. 1;

FIG. 6 is a perspective view of a second embodiment of a "trampoline frame", showing our new design;

FIG. 7 is a front elevational view of the embodiment of FIG. 6;

FIG. 8 is a side elevational view of the embodiment of FIG. 6;

FIG. 9 is a top plan view of the embodiment of FIG. 6; and,

FIG. 10 is a bottom plan view of the embodiment of FIG. 6.

The broken lines illustrate environmental elements of the trampoline frame which form no part of the claimed design.
